(57) **CLAIM**

The ornamental design for a firearm suppressor core, as shown and described.

DESCRIPTION

FIG. 1 is a top, front, right perspective view of a firearm suppressor core in accordance with our new design; FIG. 2 is a top, rear, left perspective view thereof; FIG. 3 is a top view thereof; FIG. 4 is a bottom view thereof; FIG. 5 is a front view thereof; FIG. 6 is a rear view thereof; FIG. 7 is a left side view thereof; FIG. 8 is a right side view thereof; FIG. 9 is a top, front, left perspective view thereof; FIG. 10 is a bottom, rear, right perspective view thereof; FIG. 11 is a top, rear, right perspective view thereof; FIG. 12 is a front, left perspective view thereof; FIG. 13 is a cross sectional view of FIG. 1, along line 13-13; FIG. 14 is a horizontal section of FIG. 1, along line 14-14; FIG. 15 is a vertical section of FIG. 7, along line 15-15; FIG. 16 is a vertical section of FIG. 7, along line 16-16; FIG. 17 is a vertical section of FIG. 7, along line 17-17; and, FIG. 18 is a vertical section of FIG. 7, along line 18-18. The evenly spaced broken lines in FIG. 1 and FIG. 2 depict the environment of the firearm suppressor core that forms no part of the claimed design. The dot-dash broken lines in FIG. 1 and FIG. 2 represent the orientation of the exploded view lines that form no part of the claimed design.
